UNITED STATES PATENT OFFICE.

SILAS A. McDOWELL, OF RICHLAND, OREGON.

BEET-HARVESTER.

1,333,324.

Specification of Letters Patent. Patented Mar. 9, 1920.

Application filed August 21, 1917. Serial No. 187,418.

To all whom it may concern:

Be it known that I, SILAS A. McDOWELL, a citizen of the United States, residing at Richland, in the county of Baker and State 5 of Oregon, have invented certain new and useful Improvements in Beet-Harvesters, of which the following is a specification.

This invention relates to beet harvesters.

The object of the invention is to provide a 10 simply constructed and efficient machine of this character which will effectively remove the beets from the ground, elevate them and place them in position ready to be fed to the topper.

15 With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

20 In the accompanying drawings:—

Figure 1 represents a side elevation of a beet harvester constructed in accordance with this invention.

Fig. 2 is a top plan view thereof,

30 Fig. 3 is a longitudinal section taken on the line 3—3 of Fig. 2,

Fig. 4 is a vertical section taken on the line 4—4 of Fig. 1, and

35 Fig. 5 is a similar view taken on the line 5—5 of Fig. 1.

In the embodiment illustrated, the beet harvester constituting this invention comprises a substantially U-shaped frame 1 having stub axles 2 and 3 projecting laterally 40 from the side bars thereof near their free ends and on which are revolvably mounted supporting wheels 4 and 5. Each of these wheels carries a bevel gear, the gear 6 on wheel 4 being shown secured to the inner 45 face of the wheel while the gear 7 is carried by the inner end of the hub of wheel 5. These bevel gears are designed for purposes to be described.

The cross bar 1^a of frame 1 is disposed at 50 the front of the machine and a platform 8 is carried by downwardly offset side bars 9 which project longitudinally in advance of frame 1 as is shown clearly in Fig. 3. This platform 8 is supported by a pair of front 55 wheels 10 mounted on an axle 11 carried by a hanger 12; said hanger being here shown

U-shaped with the arms thereof provided with outwardly extending lateral feet 13 which are bolted to the under side of a cross bar 14 on which the platform 8 is mounted. 60

The platform 8 is designed to support the driver's seat, not shown, it being understood that this machine is horse drawn, but it need not necessarily be so drawn, as a traction engine may be used for this purpose. 65

Another U-shaped frame 15 is disposed within the frame 1 and the side bars 16 thereof are fulcrumed at 17 to the side bars of frame 1. Mounted in this frame 15 between the rear or free ends of the arms 16 70 thereof are two disk shaped digging wheels 18 and 19, wheel 18 being provided with a solid rim 20 making it about two inches larger in diameter than the wheel 19, and this wheel is designed to be shifted on its 75 axle by means of a clutch 21 controlled by a suitable lever 22 which is held in adjusted position by the usual segmental rack 23 and spring pressed dog 23' carried by the lever. See Fig. 2.

The wheel 19 has a plurality of spokes 24 radiating therefrom and each carrying at its upper end a beet clamping plate or blade 25 which extends at its opposite ends on opposite sides of said spokes, thus forming in connection with the spokes, a substantially T-shaped member. These spokes 24 are pivotally mounted on the hub 26 of this wheel as is shown clearly in Fig. 5 and are designed to swing toward and away from the wheel 18, the rim 20 of which is inclined inwardly toward wheel 19 and cooperates with the blades 25 to grip and remove the beet from the ground over which the machine is drawn. The blades 25 are shown pivotally connected 95 with the outer ends of spokes 24 and are yieldably held in clamping position by springs 24' here shown in the form of spring metal strips secured at one end to the outer face of the spoke 24 with its free end bearing 100 against a block 25' which carries the blade 25 and which provides for yielding of the blade should it come in contact with stones or other obstructions.

A cam 27 which is here shown annular in 105 form is arranged outside the spokes 24 of wheel 19 and is preferably composed of band metal and is supported by a bar 16' projecting from the rear of one arm 16 of frame 15 and by said arm 16. This cam 27 110 operates to move the blade carrying spokes inwardly toward the wheel 18 when said

blades are disposed over the beet to be removed from the ground to clamp the beet between them.

Another cam 28 is positioned inside the spokes 24 and operates to force them outwardly when the beets reach the top of the machine over a trough 30 which is disposed between the wheels 18 and 19 and is designed to receive the beets carried up by the wheels 10 and transfer them to suitable elevating mechanism hereinafter to be described.

The trough 30 is mounted to reciprocate on rollers 31 and 32, the former of which is carried by an upright 33 which projects upwardly from an axle 34 on which said wheels are mounted. The front end of this trough 30 is supported on the roller 32 which is carried by an upstanding support or post 35 as is shown clearly in Figs. 2 and 3. The 20 trough or chute 30 has its lower end 30' extended over a trough 45 hereinafter to be described and said end is pivotally connected with the body of the chute in advance of the post 35 as is shown clearly in Fig. 3 and is designed to permit the disks or wheels 18 and 19 to be moved vertically without the chute in any way interfering with this movement.

This chute 30 which is designed to receive the beets dug out of the ground by the wheels 18 and 19 is reciprocated by means of a pitman 36 pivoted at its free end 37 thereto and at its other end connected by a wrist pin 38 carried by a disk 39 fixed to a shaft 40 mounted in upright 33 and carrying a sprocket wheel 41 over which a sprocket chain 42 passes. (See Fig. 5.) This chain also extends around a sprocket gear 43 carried by the axle 34 from which motion is imparted to said pitman 36 through disk 39 carried by said shaft 40. This oscillating or reciprocatory motion of chute 30 is designed to shake off any dirt carried by the beets and to cause them to feed downwardly 45 therethrough on to a table 44 which is arranged over the trough 45 arranged transversely of the machine at the front end thereof and in a plane at right angles to chute 30 as is shown clearly in Fig. 2.

A similar trough 46 is arranged at the rear of trough 45 and is designed to receive the tops of the beets which are cut from the beets in a manner hereinafter to be described.

55 A link 47 is connected at one end with the cross bar of frame 15 and at its other end with one arm of a bell crank lever 48 fulcrumed in suitable bearings depending from the cross bar 9" disposed at the rear of the 60 side bars 9. The other lever arm 49 is pivotally connected with a link 50 which is connected at its free end with a lever 51 carried by the cross bar on which the platform 8 is supported as is shown clearly in Fig. 3. 65 This lever 51 carries a spring pressed dog 52

which is designed to engage a toothed segmental rack 53 mounted on platform 8 by means of which the U-shaped frame 15 may be adjusted for raising or lowering the wheels carried thereby and plows 54 which 70 will be presently described.

These plows 54 are shown pivotally mounted on depending links 55 carried by the side bars 16 of frame 15 and by a bar 56 which is pivotally connected at its front end 75 with the cross bar 9" as is shown clearly in Fig. 3.

These plows 54 are made with long land sides, one right and the other left, which are positioned to run in front of and a little to 80 one side of the disks and are designed to remove the dirt from the beets and to prevent the dirt from accumulating under the disks. These plows 54 are raised and lowered as above described by the raising and lowering 85 of the U-shaped frame 15. The links 55 which support the plows are preferably provided with longitudinally extending slots 55' through which the connecting bolt 55" extends which is held in adjusted position 90 by a suitable nut so that when it is desirable to convey the machine from one field to another or over surface which it is not intended these plows shall enter, they may be elevated by lifting these links and tightening 95 up the bolts in a manner which will be obvious.

An endless conveyer 60 travels through trough 45 below the table 44, which latter terminates short of the ends of said trough, 100 and is driven by a gear 61 which receives motion from the bevel gear 7 at the right hand of the machine through a bevel pinion 62 carried at one end of a rod 63, the sprocket gear 61 being carried by the other 105 end of said rod 63. Another trough 64 is hinged at one end to the right hand end of trough 45 and as is shown clearly in Fig. 4 has an endless conveyer 65 traveling there-through for conveying the beets from trough 110 45 to a wagon or other suitable place of deposit.

Another conveyer 66 travels through trough 46 for conveying the beet tops from the trough and dumping them to one side of 115 the machine. This conveyer 66 receives motion from the driving rod 63 which operates the belt or conveyer 60 of the other trough.

A frame projects upwardly from between troughs 45 and 46 and as here shown comprises two posts as 67 from the rear faces of which project laterally extending stub shafts 68 on which are mounted sprocket wheels 69 and at the rear of said sprocket 120 wheels cutters 70 are secured. These cutters 70 may be of any suitable or desired construction, being here shown provided in the form of disks with a plurality of radially extending cutting blades 71 which are designed to rotate with their blades passing 125 130

in close proximity to the table 44 so that beets fed transversely of the table in the path of these cutters will be topped and the tops dropped into trough 46 on to the conveyer 66 which will conduct them to one end of the trough and deposit them on one side of the machine, the beets being dropped into trough 45 at either end of table 44 on to the conveyer 60 arranged below said table which will operate to conduct them to one side or the other of the machine according to the direction in which it is desired they should travel and which is controlled by means presently to be described.

15 A cross bar 72 connects the upper ends of the posts or uprights 67 and has a post 73 extending upwardly therefrom midway its length which is braced by a strap iron 74 which extends over the upper end of post 73 downwardly toward the posts 67 to which it is secured at its opposite ends by bolts or other suitable fastening elements, as is shown clearly in Fig. 4. Two sprocket gears 75 and 76 are mounted on the rear 20 face of post 73 and a sprocket chain 77 passes over these gears 75 and 76 and around the gears 69 on the stub shafts 68 which carry the cutters 70 so that when this chain is actuated both of said cutters will be simultaneously driven. Motion is imparted to this chain by means of another chain 78 which passes over the sprocket wheel 79 carried by one of the shafts 68 and around a coöperating sprocket gear 80 carried by 25 the rod 63'.

From the above description it will thus be seen that the conveyer 60 which carries the beets is driven by the rod 63 having pinion 62 at one end thereof which meshes with a 30 bevel gear 7 on the hub of the right hand driving or traction wheel 5 of the machine so that when the machine is moving forward motion will be imparted to the conveyer 60 to cause it to travel in one direction when the 35 pinion 62 is so geared. When it is desired to reverse the travel of the conveyer 60 the pinion 62 is shifted to bring it into mesh with a coöperating gear 7' carried by the axle on which wheel 5 is mounted. This 40 shifting is accomplished by means of a clutch lever 81 which is controlled by the driver at the front of the machine as is shown clearly in Fig. 2, said lever 81 being connected with a rod 82 which extends rearwardly and is engaged at one end with one arm of a bell crank 83 fulcrumed on a laterally projecting stationary supporting arm 84. This bell crank 83 engages a clutch 85 whereby the pinion 62 is caused to be engaged with either the gear 7 or the gear 7' at the will of the operator and in accordance with the direction in which it is desired that the conveyers 60 and 66 shall travel so that the beets and tops may be discharged at 50 either one side or the other of the machine.

The platform 8 carried by the front end of the machine in advance of the troughs above described is designed to contain the driver's seat, not shown, and also to provide means on which the men who feed the beets to the 70 topers may stand, it being understood that two men will be necessary to feed the beets to the two cutting knives here shown, although possibly one operator might do this work.

In the operation of this apparatus, when the machine is drawn over the rows of beets to be harvested by any suitable draft means, not shown, the disks 18 and 19 are turned on the axle 34 by the engagement of their peripheries with the ground, the plows 54 passing in advance thereof and removing the earth from the beets. These disks will then pass on each side of the beet to be dug and when in a position directly over the beet under the action of cam 27 they will close together and the continued rotation thereof will operate to pull the beet and hold it between them until it arrives at a point over the end of chute 30 when the cam 28 will force the clamping blade 25 of disk 19 away 80 from the other disk and thereby release the beet and permit it to drop into the chute 30 through which it is conveyed to the table 44 at the front of the machine. The beets deposited on this table are then taken by the 85 operators who stand on the platform 8 and have their top carrying ends fed toward the cutters 70 projecting them a sufficient distance so that the tops and crowns of the beets will be removed and will drop on to the conveyer 66 in the trough 46, while the beets are thrown off from opposite ends of the table on to the conveyer 60 which will conduct them to the side of the machine and deposit them on the conveyer 65 which will conduct them 90 to a wagon or other suitable place of deposit.

It will be seen from the foregoing description that the driver may control the plows 54 to position them for plowing or not as may be desired and that he may also either raise 100 or lower the frame 15 which carries the digging disks 18 and 19 so as to throw them either into or out of operation at will. The driver or one of the beet feeders may operate the lever 81 for changing the direction in 105 which it is desired the conveyers shall travel in the manner above set forth.

From the foregoing description, taken in connection with the accompanying drawings, the advantages of the construction and of 110 the method of operation will be readily apparent to those skilled in the art to which the invention appertains and while I have described the principle of operation of the invention together with the device which I 115 now consider to be the best embodiment thereof, I desire to have it understood that the device shown is merely illustrative and that such changes may be made as are within the scope of the claimed invention.

I claim:—

1. In a beet harvester, a wheeled supporting structure, a substantially U-shaped frame having its side members pivoted to said structure and its cross bar arranged transversely at the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute mounted for reciprocation between said wheels and to receive the elevated beets, an upright carried by said axle, a disk carried by said upright, means for rotating said disk, a pitman eccentrically connected at one end with said disk and at its other end with said chute whereby said chute is reciprocated, the front end of said chute being pivoted to move vertically and means positioned to receive the beets discharged from the chute. 45
2. In a beet harvester, a wheeled supporting structure, a substantially U-shaped frame having its side members pivoted to said structure and its cross bar extending transversely in the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute mounted for reciprocation between said wheels and to receive the elevated beets, an upright carried by said axle, a disk carried by said upright, means for rotating said disk, a pitman eccentrically connected at one end with said disk and at its other end with said chute whereby said chute is reciprocated, the front end of said chute being pivoted to move vertically and means positioned to receive the beets discharged from the chute. 50
3. In a beet harvester, a wheeled supporting structure, a substantially U-shaped frame having its side members pivoted to said structure and its cross bar extending transversely of the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute supported at its front end by a tilting frame and having said end pivoted at a point in advance of its support to move vertically relative to its body portion, means positioned to receive the beets discharged from said chute, and means for raising and lowering said tilting frame. 55
4. In a beet harvester, a wheeled supporting structure, a substantially U-shaped frame having its side members pivoted to said structure and its cross bar extending transversely of the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute supported at its front end by a tilting frame and having said end pivoted at a point in advance of its support to move vertically relative to its body portion, means positioned to receive the beets discharged from said chute, and means for raising and lowering said tilting frame. 60
5. In a beet harvester, a wheeled supporting structure, a substantially U-shaped frame having its side members pivoted to said structure and its cross bar extending transversely of the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute supported at its front end by a tilting frame and having said end pivoted at a point in advance of its support to move vertically relative to its body portion, means positioned to receive the beets discharged from said chute, and means for raising and lowering said tilting frame. 65
6. In a beet harvester, a wheeled supporting structure, a substantially U-shaped frame having its side members pivoted to said structure and its cross bar extending transversely of the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute supported at its front end by a tilting frame and having said end pivoted at a point in advance of its support to move vertically relative to its body portion, means positioned to receive the beets discharged from said chute, and means for raising and lowering said tilting frame. 70
7. In a beet harvester, a wheeled supporting structure, a substantially U-shaped frame having its side members pivoted to said structure and its cross bar extending transversely of the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute supported at its front end by a tilting frame and having said end pivoted at a point in advance of its support to move vertically relative to its body portion, means positioned to receive the beets discharged from said chute, and means for raising and lowering said tilting frame. 75
8. In a beet harvester, a wheeled supporting structure, a substantially U-shaped frame having its side members pivoted to said structure and its cross bar extending transversely of the front of the machine, an axle journaled in the free ends of said side members, a pair of digging wheels carried by said axle, one of said wheels carrying laterally movable beet clamping elements, cams for moving said elements laterally in opposite directions at predetermined intervals whereby the beets are dropped between them, a chute supported at its front end by a tilting frame and having said end pivoted at a point in advance of its support to move vertically relative to its body portion, means positioned to receive the beets discharged from said chute, and means for raising and lowering said tilting frame. 80

In testimony whereof I affix my signature in presence of two witnesses.

SILAS A. McDOWELL.
